WIRE ROPE AND METHOD OF MAKING THE SAME

Charles C. Sunderland, Trenton, N. J., assignor to
John A. Roebling's Sons Company, Trenton,
N. J., a corporation of New Jersey

Application December 26, 1928, Serial No. 328,425

11 Claims. (Cl. 117—59)

This invention relates to wire rope and to methods for making the same, the especial object of this invention being to provide an improved wire rope adapted for general operating service. 5 Operating service conditions to which wire rope may be subjected vary greatly. For example, a rope sometimes must operate at slow speed, under extremely high tension and bending over sheaves and drums of large diameter. Or the speed may 10 be extremely high, the tension may be moderate or low and the sheaves or drums may have small or medium diameters and these conditions are capable of many combinations. It would be impracticable to provide separate ropes for each 15 possible operating condition, and it is important that the rope itself when placed in service should readjust its manufactured condition to fit its operating conditions.

In the manufacture of the ordinary standard 20 wire rope, a plurality of substantially straight wires are laid up helically on a central core to form a strand and a plurality of such straight strands are laid up helically on a core to form the finished rope. The rope so formed is capable 25 of accommodating itself readily to various operating or service conditions. This can readily be seen when it is considered that in such standard ropes the wires in the strands and the strands in the ropes are not formed to definite helices so 30 that the wires and strands readjust themselves, that is, assume proper relative positions for equalizing stresses and strains.

Rope manufactured according to this standard 35 method has the disadvantage that inequalities in the wire tensions or strand tensions when closed into rope, or inequalities in size and hardness of the center, though not occurring together at any given section, tend to concentrate at one point during the course of readjustment. Such inequalities have been found to travel a considerable 40 length of rope and concentrate at the same point, with the result that rapid deterioration with consequent short rope life takes place, which would not occur if these inequalities remained 45 distributed throughout the length of the rope.

A second method of manufacture has been employed, that of the helically formed wire and strand. With this method the individual wires of the strands are formed into helices and then laid 50 about the core to form straight strands after which the straight strands themselves are formed into helices and then laid about a core to form the finished rope. In some cases, the wires and strands are formed to a helix having a slightly 55 smaller diameter than the diameter of the core

so that the wires in the strands and the strands in the rope have a tendency to hug the core.

With this construction, travel of inequalities from one section to another is prevented, but readjustment to operating conditions, also, is 60 prevented, so that such a rope does not secure maximum service under various operating conditions.

In accordance with the method of the present invention, a wire rope is provided which shall 65 have the advantage of adjusting itself to operating conditions and shall avoid the disadvantage of permitting the above inequalities to travel along its length and concentrate at certain points.

This result is secured by the provision of a 70 rope in which some of the wires in the strands are laid up in accordance with the standard method while others are formed previously into helices according to the other method, and preferably 75 the outer wires are formed into helices before laying and preferably in helices such as to secure a substantial looseness of the outside wires on the core or inside wires. The strands are then laid up on a core to form the rope, preferably 80 without previously forming them into helices. 80

The drawing illustrates a preferred form of embodiment of the invention, in which drawing:

Figure 1 is an outside view of the wire rope; and

Figure 2 is a cross section thereof.

In the drawing, the rope 1 there shown as an example, is made of a plurality of strands 2 surrounding a central core 3. Each of these strands 2 is composed of a plurality of individual wires 4 laid upon a central core 5. In the preferred 90 construction shown, the method employed in forming the rope consists in laying the inner wires 4^a unformed about the core 5 without previously forming them into helices, forming the wires 4^b into helices and then laying them on 95 the wires 4^a to form a straight strand, and then closing the rope with a plurality of these strands, preferably without first forming the strands into helices.

In a rope constructed in accordance with this 100 method, wire inequalities are prevented from traveling from one section of rope to another, while the rope is permitted to readjust itself to operating conditions.

For best results it has been found that readjustment takes place readily when the wires formed in the strand are laid with a certain degree of looseness. That is, referring to the drawing, the diameter of the helix to which the outer wires 4^b are formed is larger than the outer 110

diameter of the partial strand 2 formed by core 5 and wires 4^a. The outer wires 4^b, therefore do not hug the inner wires 4^a, but may move freely with respect to them.

- 5 It is to be understood that the degree of looseness of the wires may be varied, if desired, to meet various requirements. For example, when employing rope of this character as a sling for structural steel involving very short turns, it is 10 advisable to provide a generous amount of play of the outside wires. The looseness may therefore be increased to accommodate this situation.

While the invention has been illustrated in a construction embodying all its features in the 15 form now preferred by me, it will be understood that the invention is not limited to the specific constructions or arrangements shown but that many modifications may be made by those skilled in the art while retaining the invention defined 20 by the claims.

What is claimed is:

1. The method of making wire rope strand which comprises helically forming some of a plurality of wires, laying unformed wires about a central core, and laying said helically formed wires loosely about said unformed wires.
2. The method of constructing a wire rope which comprises forming strands by laying a plurality of unformed wires about a core, forming a plurality of wires into helices and laying said helically formed wires about said unformed wires, and laying up helically a plurality of strands so formed into a rope.
3. The method of constructing a wire rope which comprises forming strands by laying a plurality of unformed wires about a core, forming a plurality of wires into helices and laying said helically formed wires about said unformed wires, and laying up helically a plurality of strands so formed into a rope without forming the strands helically before laying them into the rope.
4. The method of constructing a wire rope which comprises forming strands by laying a plurality of unformed wires about a core, forming a plurality of wires into helices and laying said helically formed wires loosely about said unformed wires, and laying up helically a plurality of strands so formed into a rope.
5. The method of constructing a wire rope

which comprises forming strands by laying a plurality of unformed wires about a core, forming a plurality of wires into helices and laying said helically formed wires loosely about said unformed wires, and laying up helically a plurality of strands so formed into a rope without forming the strands helically before laying them into the rope.

80

6. A wire rope strand construction comprising a plurality of wires laid about a central core 85 without previously forming them into helices and a plurality of wires laid about said unformed wires and helically formed before laying them into the strand.

85

7. A wire rope strand construction comprising 90 a plurality of wires, some of the wires in said strand being helically formed before laying them into the strand and others being unformed before laying them into the strand.

90

8. A wire rope strand construction comprising 95 a plurality of inner wires and a plurality of outer wires, said inner wires being laid into the strand without previously forming them into helices, said outer wires being formed to a helix having an inner diameter larger than the outer diameter 100 of the layer of inner wires before laying them into the strand.

95

9. A wire rope comprising a plurality of strands laid up helically, each of said strands comprising a plurality of wire components laid 105 up on a core, some of said wire components being formed into helices before laying them into the strand, and others of said wires being not so formed before laying.

105

10. A wire rope comprising a plurality of 110 strands laid up helically, each of said strands comprising an inner layer of wire components laid into the strand without previously forming them into helices, and an outer layer of wire components formed into helices before laying 115 them into the strand.

110

11. A wire rope comprising a plurality of strands laid up helically, each of said strands comprising an inner layer of wire components laid into the strand without previously forming 120 them into helices, and an outer layer of wire components formed into helices before laying them into the strand and laid loosely on the inner layer.

diameter of the partial strand 2 formed by core 5 and wires 4^a. The outer wires 4^b, therefore do not hug the inner wires 4^a, but may move freely with respect to them.

- 5 It is to be understood that the degree of looseness of the wires may be varied, if desired, to meet various requirements. For example, when employing rope of this character as a sling for structural steel involving very short turns, it is 10 advisable to provide a generous amount of play of the outside wires. The looseness may therefore be increased to accommodate this situation.

While the invention has been illustrated in a construction embodying all its features in the 15 form now preferred by me, it will be understood that the invention is not limited to the specific constructions or arrangements shown but that many modifications may be made by those skilled in the art while retaining the invention defined 20 by the claims.

What is claimed is:

1. The method of making wire rope strand which comprises helically forming some of a plurality of wires, laying unformed wires about a central core, and laying said helically formed wires loosely about said unformed wires.
2. The method of constructing a wire rope which comprises forming strands by laying a plurality of unformed wires about a core, forming a plurality of wires into helices and laying said helically formed wires about said unformed wires, and laying up helically a plurality of strands so formed into a rope.
3. The method of constructing a wire rope which comprises forming strands by laying a plurality of unformed wires about a core, forming a plurality of wires into helices and laying said helically formed wires about said unformed wires, and laying up helically a plurality of strands so formed into a rope without forming the strands helically before laying them into the rope.
4. The method of constructing a wire rope which comprises forming strands by laying a plurality of unformed wires about a core, forming a plurality of wires into helices and laying said helically formed wires loosely about said unformed wires, and laying up helically a plurality of strands so formed into a rope.
5. The method of constructing a wire rope

which comprises forming strands by laying a plurality of unformed wires about a core, forming a plurality of wires into helices and laying said helically formed wires loosely about said unformed wires, and laying up helically a plurality of strands so formed into a rope without forming the strands helically before laying them into the rope.

6. A wire rope strand construction comprising a plurality of wires laid about a central core without previously forming them into helices and a plurality of wires laid about said unformed wires and helically formed before laying them into the strand.

7. A wire rope strand construction comprising a plurality of wires, some of the wires in said strand being helically formed before laying them into the strand and others being unformed before laying them into the strand.

8. A wire rope strand construction comprising a plurality of inner wires and a plurality of outer wires, said inner wires being laid into the strand without previously forming them into helices, said outer wires being formed to a helix having an inner diameter larger than the outer diameter of the layer of inner wires before laying them into the strand.

9. A wire rope comprising a plurality of strands laid up helically, each of said strands comprising a plurality of wire components laid up on a core, some of said wire components being formed into helices before laying them into the strand, and others of said wires being not so formed before laying.

10. A wire rope comprising a plurality of strands laid up helically, each of said strands comprising an inner layer of wire components laid into the strand without previously forming them into helices, and an outer layer of wire components formed into helices before laying them into the strand.

11. A wire rope comprising a plurality of strands laid up helically, each of said strands comprising an inner layer of wire components laid into the strand without previously forming them into helices, and an outer layer of wire components formed into helices before laying them into the strand and laid loosely on the inner layer.
